[57] ABSTRACT

A new mutant strain of *Bacillus subtilis* which has the property of being substantially asporogenic while showing proteolytic activity similar to that of the native strain from which it was derived. The process for preparing the new mutant strain is based on the discovery that the non-sporulated cells of *Bacillus subtilis* are not resistant to chloroform vapor whereas the spores are resistant.

3 Claims, No Drawings

ASPOROGENIC PROTEASE-PRODUCING STRAINS OF BACILLUS SUBTILIS

This invention relates to the production of enzymes from strains of *Bacillus subtilis*.

It is known that the proteolytic enzymes obtained by fermenting strains of *Bacillus subtilis* are widely used in industry, especially in the detergent industry.

However, workers exposed to the commercial-grade dust of proteolytic enzymes have been found to suffer from allergic reactions (asthma, coughing, chest pains). Similarly, certain workers have been found to suffer from allergies affecting the skin.

Although this has not been demonstrated with any degree of certainty, it is generally thought that these allergic reactions are caused by the presence of spores in commercial-grade enzymes. The standards established by common agreement between enzyme manufacturers and manufacturers of domestic detergents limit the number of spores per gram of commercial enzymes although, hitherto, these standards have been difficult to attain.

According to one of its aspects, the invention relates to a new mutant strain of *Bacillus subtilis* which has the property of being substantially asporogenic whilst showing proteolytic activity similar to that of the native strain from which it is derived.

The invention also relates to a process for mutating a native strain of *Bacillus subtilis* and isolating the asporogenic strain according to the invention.

The mutant strain obtained by this process has the same identification characteristics as the original native strain except that it does not sporulate. Its identification which is thus already possible by comparison with the well-known and defined native strain is facilitated by the fact that the mutant strain has been deposited in the collection of the Pasteur Institute in Paris and given the identification number 71-I-001.

By virtue of the fact that the mutant strain according to the invention is no different from the native strain already used in the production of protease, i.e., an extracellular enzyme used in detergents, apart from its asporogenic character, this mutant can readily be subjected to known processes for commercially growing the native strain with a view to obtaining enzymes suitable for use in household detergents.

In addition to the fact that they do not give rise to any of the allergic reactions referred to above, the enzymes thus obtained by applying a conventional process to the new mutant strain according to the invention also have the advantage of not giving off the unpleasant odour attending the use of detergents containing enzymes obtained from spore-forming strains. Finally, the absence of spores avoids any subsequent microbial growth.

Preparation of the mutant strain according to the invention is based on the following observation:

We have found that the non-sporulated cells of *Bacillus subtilis* are not resistant to chloroform vapour whereas the spores are resistant. It is thus possible to mark the colonies of asporogenic strains (sp^-) because these colonies are not replicated after exposure to chloroform vapours.

Accordingly, the process comprises (A) subjecting the spores of the native strain to a mutagenic treatment, (B) spreading the spores subjected to the mutagenic treatment over an agar-containing nutrient broth accommodated in Petri dishes to obtain after incubation

tion spore-containing colonies and (C) isolating colonies of the asporogenic strain by comparison between the homologous Petri dishes of one series emanating from operation (B) and having been subjected to treatment with chloroform vapours followed by replication and incubation, and a series having undergone the same operations except for exposure to the chloroform vapours, and finally (D) selecting the mutant strain satisfying the required sporulation conditions from the mutant strains isolated showing proteolytic activity.

In one embodiment of this process, the mutagenic treatment (A) of the spores of the native strain of *Bacillus subtilis* comprises initially heating a suspension of spores for 10 minutes to 70°C., followed by germination in Difco nutrient broth in the presence of chloramphenicol (100 μ g/ml), the culture being stirred for 2 hours at 39°C., and finally by the actual mutagenic treatment with N-methyl-N'-nitro-N-nitrosoguanidine (50 μ g/ml), the culture being stirred for 1 hour at 37°C. The culture medium used for germination has the following composition:

for 1 litre of distilled water	
Difco nutrient broth	8 g
MgSO ₄ ·7H ₂ O	0.25 g
KCl	1.0 g
MnCl ₂ ·4H ₂ O - 10 ⁻³ M	1 ml
FeSO ₄ ·7H ₂ O - 10 ⁻³ M	1 ml
CaCl ₂ ·H ₂ O - 1.5%	10 ml
NaOH . . . quantity sufficient to adjust pH to 6.8 - 7.0	

35 A dilute form of the suspension of spores germinated and treated with the mutagenic agent in accordance with the foregoing is spread (operation B) over agar-containing Difco nutrient broth accommodated in Petri dishes (series I). To this end, the medium used has the same composition as that used for germination, but additionally contains 20 g/litre of agar. After incubation for 48 hours at 37°C., the sp^+ colonies contain spores.

40 Isolation (C) which includes a treatment with chloroform vapours applied to certain colonies comprises the following operations:

- colonies of series I are replicated in other Petri dishes containing the same medium (series II);
- colonies of series I are then exposed to chloroform vapours for 45 minutes at the temperature of the laboratory, after which the colonies thus treated are replicated in a new series of Petri dishes (series III);
- series II and III are incubated for 24 hours at 37°C.;
- the homologous dishes of series II and III are compared.

60 The sp^- colonies are absent from series III but present in series II because the cells are killed by the chloroform vapours. Samples of the sp^- colonies are taken from series II and then isolated again. After the second isolation, the strain retained for their sp^- character are tested for their proteolytic activity. To this end, the medium used is preferably agar-containing Difco nutrient broth with casein added. For example, a Difco medium of the following composition is used:

for 1 litre of distilled water	
Difco nutrient broth	16 g
MgSO ₄ ·7H ₂ O	0.50 g
KCl	2.0 g
MnCl ₂ ·4H ₂ O - 10 ⁻² M	2 ml
FeSO ₄ ·7H ₂ O - 10 ⁻⁹ M	2 ml
CaCl ₂ ·2H ₂ O - 1.5%	20 ml
NaOH . . . quantity sufficient to adjust pH to 6.8 - 7.0	
agar	20 g

The medium is mixed in equal volumes with a solution containing 20 g of casein per litre of distilled water, the pH-value being adjusted to 6.8 - 7.0.

The colonies showing proteolytic activity (Pr⁺) are surrounded by a proteolysis ring.

Selection (D) of the mutant strain is made as follows:

Out of 35,000 colonies examined in series I, seven mutant strains were isolated. They were studied in liquid Difco nutrient broth with the same composition as the broth previously used for germinating the spores in order accurately to determine their sporulation rate and the level of proteolytic activity.

The substrate used for measuring proteolytic activity is azocasein. The reaction mixture contains 1 ml of a 0.5% azocasein solution in a Tris buffer (tris-[hydroxy methyl amino methane]) 0.1M at pH 8.5, and an aliquot portion of a supernatant phase of centrifuged culture. The volume is made up to 1.5 ml with the Tris buffer. After the mixture has been incubated for 30 minutes in a water bath at 37°C., the non-hydrolysed azocasein is precipitated with 2 ml of 10% trichloroacetic acid. The mixture is filtered. 1.5 ml of 0.5 N NaOH are added to 1.5 ml of the filtrate, followed by a reading at 440 nm. One unit (UA) corresponds to 1 mg of azocasein hydrolysed for 30 minutes at 37°C. under the conditions specified above.

The results are set out in Table I below:

strain	proteolytic activity UA/ml	sporulation sp/ml.
B native	14	8.10 ⁷
B 12	14	0
B 22	1	0
B 61	9	5.10 ⁴
50		
Mutants		
B 82	16.3	1.4 · 10 ³
B 111	2.8	0
B 112	11	4.4 · 10 ⁴
B 143	14.5	1.2 · 10 ⁵

Of the 7 mutant strains which were isolated, only 3 are asporogenic and only one, designated B12 although it has already been deposited and bears the identification number specified earlier on, has a level of proteolytic activity similar to that of the native strain. Comparison of the mutant strain B12 with the native strain

a. Morphology of the cells

1. In the liquid Difco nutrient broth having the same composition as that indicated above the the germination phase (A) and for examining the mutant strains in phase (D).

Native strain

Labile rod (width 0.8 to 1.0 μ ; length 2.4 to 2.6 μ). In the exponential growth phase, the cells are in the form of more or less long chains (4 to 10 cells). After

growth, the chains are shorter (2 to 4 cells) and the cells are less long.

Gram-positive colouration.

The spores formed are oval (0.8 μ /1.1 μ).

5 Mutant strain

Identical, but does not form spores.

2. Appearance of colonies on the solid agar-containing Difco nutrient broth having the composition specified for treatment (B) with the mutagenic agent.

10 Native strain:

Round, white, dull smooth-edged colonies flattened at the centre and opaque. After 48 hours at 37°C., a yellow pigment is excreted.

15 Mutant strain

Identical colonies except that, after 3 to 4 days at 37°C., the colonies become translucent (destruction of the cells). Yellow pigment is again excreted.

b. Physiology

20 Growth in Difco nutrient broth having the same composition as the media used for the germination operations (A), for examining the mutant strains in phase (D) and for examining the morphology of the cells (a) above.

	Native strain	Mutant strain
Growth rate at 30°C (division/hour)	$\mu_1 \sim 0.49$ $\mu_2 \sim 0.32$	$\mu_1 \sim 0.49$ $\mu_2 \sim 0.32$
Number of cells (maximum/ml)	~ 9.10 ⁸	~ 9.10 ⁸
Proteolytic activity in UA/ml *	~ 14	~ 14
Number of spores/ml	~ 8.10 ⁷	0
Prototrophy	+	+

*The method used is that which was described earlier on and which uses a 0.5% solution of azocosein in the Tris buffer 0.1 M at pH 8.5.

40 The proteolytic enzyme is excreted in the medium on completion of growth. Maximum activity is reached approximately 12 hours after the beginning of excretion.

c. Comparison of the properties of the enzymes excreted by the native strain and the mutant strain

1. Heat resistance.

a. Having reached maximum proteolytic activity, the cells of one culture are eliminated by centrifuging. Aliquot portions of the supernatant phase are heated in a water bath for 10 minutes at different temperatures (40°, 45°, 50°, 55° . . . 75°C). The residual proteolytic activity is measured by the process described above. The percentage of residual proteolytic activity is recorded on a graph as a function of temperature for the two types of enzyme. It is found that, in both cases, the temperature at which 50 percent of the original activity is still present is approximately 70°C.

b. Aliquot portions of the supernatant phase are heated at 70°C. in a water bath for different periods (2, 5 . . . 20 minutes).

60 A/A₀ is recorded on the graph as a function of time *t* in minutes (A being the residual activity and A₀ being the original activity). Equation lines are thus obtained:

65 $\log A/A_0 = -kt \log e$ for a temperature of 70°C. The gradient of each straight line [*k* log *e*] makes it possible to determine the velocity constant of the denaturation reaction (*k*). If more than one straight line is obtained,

it means that there is more than one enzyme in the supernatant phase. The gradient of each straight line is characteristic of an enzyme.

The gradients observed for the enzymes of the mutant and of the native strain suggest that the supernatant phases contain two proteolytic enzymes of which one shows hardly any resistance to heat.

So far as the most resistant enzymes are concerned, the gradients $k \log e$ are the same for the enzyme emanating from the mutant and for the enzyme emanating from the native strain. For these enzymes, the velocity constant of the denaturation reaction is:

$$k (70^\circ\text{C}) = 0.1 \text{ min}^{-1}$$

2. Comparison of proteolytic activity in Tris medium and in borate-polyphosphate medium.

Starting with the same supernatant phase, determination is carried out at 37°C . either with the Tris buffer (tris-[hydroxyl methyl amino methane]) at pH 8.5 or with a buffer of pH 8.5 containing 3 g/l of borate and 3 g/l of polyphosphate.

The activities obtained with one or the other medium are identical both for the mutant and for the native strain.

3. Inhibitors

a. The enzymes of the mutant and of the native strain are not inhibited by α -phenanthroline hydrochloride (10^{-3}M).

b. The degree of inhibition caused by diisopropyl fluorophosphate (10^{-3}M) is of the order of 95 percent for the mutant and the native strain. Accordingly, the principal enzyme would be seryl-protease in both cases.

Overall, the foregoing examination shows that the mutant strain according to the invention is an asporogenic mutant of the native strain of *Bacillus subtilis* which does not have any effect either upon production or upon the properties of the extracellular protease, i.e., the enzyme produced by fermentation from the strain, except in regard to the formation of spores.

The enzyme produced by fermentation of the *Bacillus subtilis* strain is present in solution in the aqueous phase of the culture broth. The following procedure can be adopted for producing the enzymes according to the invention on a commercial scale:

A fermentation process is carried out in a variable-sized fermenter aerated in depth, agitated and equipped with a heat-regulating system. The culture medium contains organic nitrogen compounds such as distillery residues, maize maceration liquor, soya flour, casein, mineral elements etc. This culture medium is inoculated with an asporogenic *Bacillus subtilis* culture (strain according to the invention as deposited) obtained in agitated flasks or from an inoculum fermenter.

The aeration required amounts for example to between 100 and 500 m^3 per hour for a fermenter with a useful capacity of 15 m^3 .

Fermentation is carried out at 37°C . However, the fermentation temperature can be in a range from 30° to 38°C . The pH-value is adjusted to 7.0 at the beginning of fermentation.

After having been inoculated, the culture medium is sterilised with live steam for 30 minutes at 121°C .

The air injected at the bottom of the fermenter is sterilised by passage through a cylinder filled with glass wool.

On completion of fermentation, the liquid phase is separated from the bacteria and solid particles by fermentation, generally in a filter press comprising a Nylon cloth. A filtration additive is added to the fermentation juice to be filtered.

15 The filtrate is precipitated with a solvent such as ethanol, butanol, or even with ammonium sulphate. The precipitate obtained is centrifuged in a centrifuge, for example of the "Sherpless" type and filtered in a filter press. The wet cake obtained is introduced in trays into an oven in which it is dried in vacuo at a temperature not exceeding 60°C .

20 The powder obtained does not contain any spores. It can be used in detergents made up in accordance with the usual formulations and does not produce any of the 25 allergic reactions observed with enzymes obtained from sporular strains.

We claim:

1. A process for selecting asporogenic bacteria from the genus *Bacillus subtilis* which comprises:

a. mutating germinated spores of wild *Bacillus* and spreading the spores subjected to the mutagenic treatment over an agar containing nutrient broth accommodated in a series of Petri dishes to obtain after incubation colonies containing spores;

b. replicating each Petri dish of said series to obtain a first homologue series of Petri dishes;

c. submitting each Petri dish of said first mentioned series to chloroform vapor and replicating it to obtain a second homologue series of Petri dishes;

d. incubating said first homologue series and said second homologue series of Petri dishes;

e. by comparison between homologue Petri dishes of said first homologue series and said second homologue series, selecting the asporogenic mutant strains which are strains of said Petri dishes of said first homologue series which are not in the Petri dishes of said second homologue series; and

f. testing proteolytic activities of these selected strains on casein.

2. Process for preparing protease without spore which comprises culturing in a known manner for the wild *Bacillus subtilis* an asporogenic bacteria selected by the process of claim 1.

3. Process according to claim 2 wherein asporogenic bacteria is a *Bacillus subtilis* of the type identified by No. 71-I-001 deposited in "Institut Pasteur de Paris."
